UNITED STATES PATENT OFFICE

NATHAN M. LOWER, DAVID F. CRAWFORD, AND EDWIN ARCHER TURNER, OF PITTSBURGH, PENNSYLVANIA, ASSIGNEES, BY MESNE ASSIGNMENTS, TO THE STANDARD STOKER COMPANY INC., OF NEW YORK, N. Y., A CORPORATION OF DELAWARE

INSIDE FEED STOKER

Application filed January 8, 1926, Serial No. 79,977. Renewed March 22, 1930.

This invention relates to stoker mechanism and more particularly to stokers of the underfeed type.

One of the objects of the invention is the provision of an underfeed stoker in which fuel is delivered at a plurality of points in the rear portion of the firebox from which it is distributed over the grates.

Another object of the invention is the provision of a conveyer having conduits leading therefrom to the firebox together with a new and improved conveyer member for forcing fuel through said conduits.

A further object of the invention is the provision of an underfeed stoker having one or more fuel conduits for delivering fuel to the firebox above the grates, with new and improved means for cooling the delivery end of said conduits.

Another object of the invention is the provision of a new and improved stoker conveyer having the operating mechanism mounted on the tender.

A still further object of the invention is the provision of a new and improved underfeed stoker that is cheap to manufacture, easily assembled, that will occupy a minimum amount of space on the locomotive, that is efficient in operation, rugged, durable, light in weight, composed of few moving parts, and that is sufficiently flexible to accommodate the relative angular movements between the locomotive and tender, at all times.

Other and further objects and advantages of the invention will appear from the following description taken in connection with the accompanying drawings, in which

Fig. 1 is a vertical section of a portion of a locomotive and tender therefor, showing the stoker mechanism in position thereon;

Fig. 2 is a vertical section of a portion of the rear end of a locomotive on the line 2—2 of Fig. 1;

Fig. 3 is a section on line 3—3 of Fig. 2, with parts broken away;

Fig. 4 is a view somewhat similar to Fig. 2, showing a modified form of construction;

Fig. 5 is a similar view showing a still further modified form of stoker construction;

Fig. 6 is a horizontal section of the rear portion of a locomotive showing the forward portion of the stoker in position thereon, shown more or less diagrammatically, with parts in section and parts broken away;

Fig. 7 is a plan view of the forward portion of the conveyor and the rear portion of the transfer conduits, with parts broken away; and

Fig. 8 is a section on line 8—8 of Fig. 6.

On the drawing, the reference character 10 designates a locomotive having the backhead 11, firedoor opening 12, firebox 13 and grates 14 therein, all of which are of the usual or any well known construction. The tender is shown at 15 and comprises a fuel tank 16 having the usual elongated opening 17 in its bottom wall.

The fuel is transferred from the tender to the locomotive by a suitable conveyer. As shown, the conveyer comprises front and rear sections 18 and 19 respectively. The rear portion of the conveyer terminates in a trough 21 located beneath the opening 17 for receiving the fuel from the tank 16. The front and rear sections are connected together by a universal joint 22 which permits of the necessary relative angular movement between the locomotive and tender during their travel around curves and the like.

A conveyer screw, which may comprise the sections 25 and 26 connected by a universal joint 27 is rotatably mounted in the casings 18 and 19. The joint 27 is arranged in the plane of the universal joint 22 in order that the relative movement of the locomotive and tender will not interfere with the operation of the screw.

The conveyer screw is operated from its rear as by a motor 27 located beneath the deck of the tender. Owing to the restricted space, a small four-cylinder engine having the common intake and exhaust ports 28 and 29, is employed, the piping being omitted on the drawing for the sake of clearness. The conveyer screw is connected to the engine crank shaft by a telescopic connection 31, a set of reducing gearing being interposed if necessary or desirable.

The front end of the casing is provided with

laterally extending or branch conduits 32 and 33 to which are detachably connected the elevator casings or conduits 35 and 36 as by means of the bolts 37. The casings extend upward through the grates in the rear corners of the firebox. They may be removed by releasing them and lifting them upward into the firebox after which they may be removed through the firedoor opening if necessary or desirable.

The upper ends of the elevator casings extend upward through the fuel bed and unless protected they will soon be destroyed by the intense heat. Suitable means are provided for shielding them from this heat. As shown they are protected by water pipes. Preferably a series of pipes 38 are employed. Each pipe extends about the exposed side of the upper end of an elevator casing and has its ends secured in the walls of the firebox, one end being at a higher elevation than the other whereby a free circulation of the water from the water leg of the boiler is insured. The upper ends of the elevator casings are preferably provided with flanges 39 which extend over the top of the uppermost water pipe 38.

In order to distribute the fuel over the grates, a pair of nozzle blocks 41 are provided. The blocks are located in the corners of the firebox in rear of the elevator casings and the blast from each is directly rearward and toward the center of the firebox. They are supplied with steam through the pipes 42 which extend upwardly in the corners of the firebox in rear of the casings whereby they are protected from the heat of the furnace.

The front end of the conveyer screw extends across the branch or laterally extending conduits and is preferably, though not necessarily, provided with a double flight 43 and 44 whereby the fuel is evenly divided between the two branches. The flights 43 and 44 may be extended forwardly parallel with the axis of the conveyer at their forward ends to form the paddles 60 and 70 for preventing packing of the fuel between the end of the conveyer and the wall of the casing.

In the operation of the device, fuel is conducted forwardly by the conveyer and forced laterally and upwardly through the elevator casings. As it boils up above the upper ends of the casings it is projected by steam blasts to all parts of the firebox. By locating the elevators in the rear corners of the firebox a supply of fuel is insured in these corners and each nozzle is required to distribute the fuel over only approximately one half of the grate area. This is considered an important feature of the invention because it insures a very efficient distribution of the fuel.

From the foregoing description of the preferred embodiments of this invention, it will be seen that the elevator casing or conduits

35 and 36 extend into the firebox a substantial distance above the grates thereof to obtain the necessary height from which the fuel can be scattered over the fire bed in aerial paths by the blast from the nozzle block, 41, and that the forward ends of the conduits which are exposed to the intense heat of the burning fuel are protected by water cooling means, which as shown is in the form of a series of pipes, but may be of any construction that provides a protecting wall having a circulation of fluid therein for the purpose heretofore described. The use of the cooling means or protecting wall is equally applicable to other forms of stoking apparatus which provides only one elevating conduit projecting into the firebox.

The form of the device shown in Fig. 4 differs from that shown in Figs. 1 to 3 in that the elevator casings 45 and 450 do not extend above the grates 14. The openings in the nozzle 46 are inclined slightly upwardly in order to project the fuel over the firebed.

In the form of the device shown in Fig. 5 the elevator casings 47 and 48 terminate at the grates as in Fig. 4. The nozzles 49, however, are located at a distance above the upper end of said casings whereby a supply of fuel is maintained in the rear corners of the firebox, none of the fuel being projected forwardly by the blast from said nozzle until it is built up in front of the nozzle.

If desired the pipes 51 for supplying steam to the distributor nozzles 47 extends through the backhead of the locomotive, as clearly disclosed in Fig. 5.

The joint 22 in the conveyer is located adjacent to the coupling 50 between the locomotive and the tender whereby the front end of the conveyer will have a minimum movement relative to the tender in making curves. The motor 27 for operating the conveyer being carried by the tender relieves the engine of this additional weight.

In Figs. 6, 7 and 8 are shown a modified form of the device in which the transfer conduits 52 and 53 extend forwardly from the conveyor casing 54 and diverge laterally. They merge into a rearward extension 55 to which the connecting member 56 is rigidly secured. The forward end of the conveyor 54 has a convex outer surface which is pivoted in the connecting member 56 in the usual manner.

The transfer conduits 52 and 53 have their forward ends extending upwardly in a plane transversely to the axis of the conveyor and projecting through the grates 14 adjacent to the back wall 11 of the firebox 13. These upwardly extending ends 57 and 58 may be flush with, or extend above, the grates as in the previous construction. Where they extend above the grates as shown in Fig. 8 the exposed ends are protected by the water tubes as in the construction described above. The

nozzles 59 are arranged in the same manner as the blocks 41 described above and perform the same function.

The conveyor casing 54 is provided with a conveyor screw 61 which is adapted to transfer fuel from the tender and force the same in a continuous stream through each conduit 52 and 53 into the firebox where it is distributed by blasts from the nozzles over the grates.

In order to properly divide the fuel delivered by the conveyor to the transfer conduits 52 and 53 a divider member 62 is mounted in the extension 55 to swing about a vertical pivot member 63. The pivot member 63 is journaled in the extension 55 and is provided with an arm 64 having an arcuate slot 65 therein through which a pin, tapped in the extension, extends and is adapted to hold the plate and with it the divider member 66 in adjusted position for controlling the proportionate amount of fuel delivered to each conduit.

In the operation of the device, the screw 61 conveys the fuel forwardly from the tender 25 and forces the same forwardly through the conduits into the firebox in continuous or unbroken streams.

It is thought from the foregoing taken in connection with the accompanying drawings 30 that the construction and operation of our device will be apparent to those skilled in the art, and that various changes in size, shape, proportion and details of construction may be made without departing from the spirit 35 and scope of the appended claims.

We claim as our invention:

1. In combination, a locomotive having a firebox, a tender, a fuel conveyor for transferring fuel from said tender to said locomotive, a plurality of conduits for transferring the fuel from said conveyor to said firebox, the forward ends of said conduits extending into said firebox and a substantial distance above the grates thereof from which 45 the fuel can be scattered over said grates in aerial paths, and water cooled means for protecting the exposed ends of said conduits from the heat of the burning fuel.

2. In a furnace having a firebox with hollow walls, a fuel delivering conduit located within a corner of the box, means for forcing fuel through the conduit, and means for protecting the conduit from the furnace heat, comprising a conduit having its ends in communication with the chambers of adjacent firebox walls.

3. In a furnace having a firebox with hollow walls, a fuel delivery conduit located within a corner of the box, means for forcing fuel through the conduit, means for protecting the conduit from the furnace heat, comprising a plurality of pipes having their ends at different altitudes and connected respectively with the chambers of adjacent firebox walls.

4. In combination, a locomotive having a firebox, a fuel conduit having its forward end extending into said firebox a substantial distance above the grates thereof and from which the fuel can be scattered over said grates in aerial paths, and means for circulating water from the boiler of said locomotive about the forward end of said conduit for protecting the same against the heat generated in said firebox.

5. In combination, a locomotive having a firebox, a fuel conduit having its forward end extending into said firebox a substantial distance above the grates thereof and from which the fuel can be distributed thereover in aerial paths, and water cooling means for protecting the forward end of said conduit from the heat generated in said firebox.

In testimony whereof we affix our signatures.

NATHAN M. LOWER.
DAVID F. CRAWFORD.
EDWIN ARCHER TURNER.
